UNITED STATES PATENT OFFICE

2,616,322

POWER-OPERATED MAGAZINE WRENCH

Charles Gottlieb Spreng, Denison, Iowa

Application February 17, 1949, Serial No. 76,997

3 Claims. (Cl. 81—52.4)

1

This invention comprises novel and useful improvements in a power operated magazine wrench and more specifically pertains to an improved wrench of the magazine type for facilitating the application of nuts to bolts and the like.

The primary object of this invention is to provide a magazine wrench which shall be capable of selective operation by power or manual means while performing its functions as a magazine wrench.

A further important object of the invention is to provide a magazine wrench having a readily applied or removed overload release coupling for applying nuts with a predetermined force to bolts and studs.

Yet another object of the invention is to provide a magazine wrench which shall be operated by a non-reversible power drive.

A still further object of the invention is to provide a wrench in accordance with the preceding object but which shall be capable of ready adaptation and rearrangement of its components for selectively driving the magazine wrench in reverse directions as desired.

A still further object of the invention is to provide a magazine wrench in conformity with the foregoing objects but wherein there is provided a readily adjustable overload release clutch for preventing the application of greater than a predetermined force to a nut while the same is being threaded upon a bolt or stud.

And a final important object of the invention to be specifically numerated herein, is to provide a magazine wrench which is capable of operation either manually or by power and wherein there is provided an improved yieldable nut retaining means.

These, together with various ancillary features and objects of the invention which will later become apparent as the following description proceeds, are attained by this device, a preferred embodiment of which has been illustrated by way of example in the accompanying drawings, wherein:

Figure 1 is a side elevational view of a preferred embodiment of the improved magazine wrench in accordance with the principles of this invention;

Figure 2 is a top plan view of the arrangement of Figure 1;

Figure 3 is a vertical longitudinal sectional view, taken substantially upon the plane of the section line 3—3 of Figure 2;

Figure 4 is a horizontal sectional detail view taken substantially upon the plane of the section line 4—4 of Figure 3 and showing in particular

2

the irreversible driving mechanism for the magazine wrench;

Figure 5 is a group perspective or assembly view of the components of the overload release clutch forming a part of the invention;

Figure 6 is a horizontal sectional view taken substantially upon the plane of the section line 6—6 of Figure 3 and showing in particular the arrangement and mounting of the resilient nut retaining means for the magazine of the device; and,

Figure 7 is a perspective view of the nut retaining resilient member forming an element of the invention.

Referring now more specifically to the accompanying drawings, wherein like numerals designate similar parts throughout the various views, attention is directed first to Figure 1 wherein the numeral 10 designates generally the gearing assembly unit for driving the magazine wrench, through the agency of a driving member 12, while the numeral 14 designates generally the overload release coupling which is interposed between the driving assembly 10 and the magazine wrench 16.

Referring now more particularly to Figures 3 and 4, it will be understood that the member 12 which constitutes a source of power for operating the power operated magazine wrench, may comprise the terminal and connecting portion of a flexible shaft, or any other connecting member by means of which a prime mover, not shown, and which may conveniently comprise a portable hand type of electric drill or the like, is connected by an enlarged socketed end portion 18 having a non-circular socket or recess 20 therein for the reception of a correspondingly shaped extremity 22 by means of which the wrench gearing is operated.

The gear casing 10 includes a container 24 of sheet metal or the like, and which is provided with a removable closure 26 at one side thereof, which is provided with inturned flanges 28 by means of which the closure is removably retained upon the casing 24 as by screws 30 or the like. Also provided on the closure 26, is a conventional form of lubricant fitting 32 by means of which grease or lubricant may be supplied to the interior of the gear casing for lubricating the parts therein.

The casing 24 is preferably provided with a bushing 34 forming a journal bearing, which together with the grease retaining packing ring 36, rotatably receives the bearing portions 38 and 40 whereby is journaled a transversely disposed worm gear 42, whose outer extremity is provided

55

with the previously mentioned non-circular portion 22 by means of which the worm gear is rotated.

This worm gear is continuously in mesh with gear teeth 44 constituting a pinion formed upon a rotor 46 in the form of a disk or the like, which rotor as shown in Figure 3 is provided with oppositely and axially extending sleeve or hub portions 48 and 50 which extend through the upper and lower walls of the gear casing 24. Suitable oil retaining washers or packings 52 and 54 are provided between the opposite sides of the rotor and the upper and lower walls of the gear casing.

The extending sleeves are provided with sockets which are non-circular in cross section, as indicated at 56 and 58, and either of which may be selectively engaged by a similarly shaped axial extension 60 formed upon and carried by the closed end wall portion 62 of a cup-shaped member 64.

This cup-shaped member which constitutes the casing of the overload release clutch coupling previously mentioned, is internally threaded at its open end as at 66 and upon the inner surface of its end wall as at 68 has rigidly secured thereto a friction lining 70 in the form of a disk or the like. Loosely received within the hollow interior of the member 64, is a metallic disk 72 to which is rigidly attached in any suitable manner a driving stem 76 which is loosely received in the central aperture of a steel washer 74 constituting a bearing for the lower surface of the disk 72. The steel washer 74, and thereby the disk 72 and stem 76 are retained within the interior of the cup-shaped member 64 by an externally screw threaded packing member or gland 77, through which loosely and rotatably extends the stem 76. The lower end of the stem 76 is preferably squared as at 78 to provide means for effecting a snap fitting engagement in the socketed end 80 of a nut magazine 82 which forms the wrench member of the device.

As shown in Figure 3, the magazine 82 is of a non-circular shape in cross section, which shape corresponds to the shape of the particular nuts which the wrench is intended to manipulate, these nuts being indicated therein as at 84.

The member 82 may be of any desired length, and it is contemplated that various dimensions of such magazines may be employed whereby the wrench is capable of applying nuts of different dimensions. At its lower end, the magazine 82 is provided with lateral slots 86 and a resilient nut retaining member, of the construction indicated in Figures 6 and 7, is adapted to have inwardly curved and resiliently inwardly urged portions 88 received and retained in the slots 86 for retaining yieldingly in the magazine 82 the previously mentioned nuts 84.

The spring member 90 having the portions 88 is adapted to snugly embrace the periphery of the magazine 16, as will be apparent from Figures 1 and 6, whereby the inwardly curved portions 88 are adapted to be yieldingly urged and retained in the slots 86 to thereby retain the member in position in the magazine, as well as to provide a yielding obstruction preventing unintentional removal of the nuts 84 from the magazine, and yet permitting a nut to be forcibly withdrawn from the magazine as desired.

The operation of the device previously described is as follows. With the member 22 inserted in the socket 20 of the driving member

12 connected with a suitable source of power, the rotor 46 will be power driven in an irreversible manner. By a suitable connecting member, not shown, the socketed end 80 of the magazine 82 may be connected with either of the sockets 56 or 58 of the rotor, whereby the magazine wrench may be driven in either direction as desired. However, it is preferred to connect the socket 80 to the rotor 46 by the interpolation therebetween of the overload release coupling 14. For this purpose, the terminal portions 60 and 78 of the clutch coupling are respectively seated in one of the sockets 56 or 58 and in the socketed portion 80 of the magazine 82, whereby the magazine may be rotated by the member 12 in either direction. It will be noted that the gland 77 retains the clutch or coupling elements within the cup-shaped member 64, and by means of adjusting the gland 77 within the screw threads 66, any predetermined pressure may be applied between the disk 72 and the friction lining 70, whereby a frictional driving engagement is established between the inner surface 68, the lining 70 rigidly attached thereto, and the disk 72 frictionally coupled to the lining, whereby the stem 76 will rotate the magazine 82. However, when the nut has been tightened upon a bolt or stud with a force determined by the frictional driving force exerted by the lining 70 on the disk 72, a slippage will occur between these parts of the clutch member, to thereby prevent the application of greater than a predetermined force to the nut being tightened.

When it is desired to operate the wrench manually, it is merely necessary to remove the gear casing 10 and apply a suitable handle to the extension 60, or if desired to also remove the overload release coupling 14 and apply a suitable handle to the socket 80, to thereby manually manipulate the magazine wrench.

From the foregoing, the construction and operation of the device will be readily understood. It will be seen that the device is particularly adapted for use in assembly line operation as for rapidly applying a plurality of identical nuts with the same force to studs or bolts, as for applying head bolts to automobile engines in manufacturer's assembly lines.

However, the device obviously lends itself to many other uses where the advantages of selective power or manual operation, easy reversibility, and adjustable overload releasing of the drive of the wrench are important desideratum.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A power operated magazine wrench comprising a casing having a rotor journaled therein and having socketed ends extending through opposite walls of said casing, means journaled in said casing and extending exteriorly thereof for driving said rotor, a magazine for slidably and non-rotatably receiving and retaining a

plurality of nuts therein, means detachably and drivingly connecting said magazine selectively to one of the socketed ends of said rotor.

2. A power operated magazine wrench comprising a casing having a rotor journaled therein and having socketed ends extending through opposite walls of said casing, means journaled in said casing and extending exteriorly thereof for driving said rotor, a magazine for slidably and non-rotatably receiving and retaining a plurality of nuts therein, means detachably and drivingly connecting said magazine selectively to one of the socketed ends of said rotor, said last means including an adjustable overload release coupling, said coupling having connections for attachment to said rotor and to said magazine.

3. A power operated magazine wrench comprising a casing having a rotor journaled therein and having socketed ends extending through opposite walls of said casing, means journaled in said casing and extending exteriorly thereof for driving said rotor, a magazine for slidably and non-rotatably receiving and retaining a plurality of nuts therein, means detachably and

drivingly connecting said magazine selectively to one of the socketed ends of said rotor, said magazine comprising a casing having a nut receiving chamber open at its lower end and of non-circular cross section, lateral slots extending through said casing at its open end, a spring nut retaining clip embracing said casing and having portions extending through said slots into said chamber for yieldingly embracing a nut therein.
